SPINNING CENTRIFUGAL MOTOR
ARRANGEMENTShuzo Odajima, Toba-machi, Shima-gun, Japan,
assignor to Kobe Seiko-sho, Ltd., Kobe, Japan

Application October 9, 1934, Serial No. 747,517

1 Claim. (Cl. 117—27.5)

This invention relates to spinning centrifugal motor arrangements and particularly to an arrangement for eliminating the vibration of the pot wherein a movable revolving weight is placed on the lid of the case covering the motor and wherein a guide is provided between the case and the pot.

An object of this invention is to provide a device of this type capable of controlling vibrations of the motor and case for the purpose of saving consumption of electric power.

As it is well known, air disturbances created by the revolutions of the pot are sufficiently powerful to increase the consumption of electric power while operating a spinning centrifugal motor. If the pot is covered by a case provided with a lid, substantially conforming to the contour of the pot but a little larger in size, so that a narrow space is left around the pot, the consumption of electric power is reduced in a remarkable degree for the reason that the volume of air, which is disturbed by the revolutions of the pot, is limited to that confined within the case. However, such arrangements render the operation of the motor unstable for the following reasons:—

If the pot is covered by the case, it is practically impossible to provide a free space of the same dimensions between the covering case and the pot so that various currents of air will be produced around the pot by its revolutions and, naturally, the pressure upon one part of the covering case and lid will be different from that upon another part, which will cause the case and lid to start vibrating vertically and horizontally. Vibrations thus caused, increase gradually, and make it impossible to keep the motor further in operation.

In order to control such vibrations, a lid of heavy weight may be used, or the case and lid may be connected with some external fixture, but both these methods are in practice quite inconvenient for spinning purposes in view of the fact that it is frequently necessary to remove the lid from the motor in operation. Another method is to avoid the use of the lid or to make holes on the side walls of the case in order to render air pressure uniform all around the pot, but this method does not succeed in lessening the volume of air disturbed by revolutions of the pot, or in saving the consumption of electric power.

By these well known methods, percussions of the pot against the covering case cannot be avoided when the motor is put into motion or when

the brakes are applied, which, consequently, causes considerable wear of the pot.

By experiment, I found that when a proper guide was provided between the pot and the case and at the inside thereof, the percussions of the pot against the case when the motor was put into motion could almost be eliminated, rendering the motion of the motor stable after a short time. For instance, if a ring-formed guide is fixed to the inside of the case, the motion of the motor will become smooth for the reason that the vibration of the pot at the time the motor is put into motion, is considerably reduced because of the narrow space between the pot and the guide. The percussions of the pot against the covering case can be entirely eliminated if the guide is provided between the shaft of the pot and the base of the covering case, and the space between the guide and the shaft is narrower than the space between the pot and the covering case as shown in the attached drawing.

In order to control the vibration of the pot and case after the motor has been put into motion and during further operation, thereof, I fixed on the lid, a proper weight and investigated the result of the experiment by changing the position of the fixed weight on the lid and found that the vibration could be controlled when the weight was placed close to the shaft. It was furthermore found that the closer to the shaft the weight was placed, the lighter a weight could be used to control the vibration. As a result of this experiment, I found that a lighter weight will serve the purpose if the same is fixed exactly at the center of vibration upon the surface of the lid. The center of vibration may technically be said to coincide with the center line of the axis of the motor, but it is practically impossible to make the center of vibrations to coincide exactly with the center line of the axis of the motor, and, therefore it is hardly possible to fix the weight upon the center of vibrations on the lid, even after such center has been determined.

Another experiment was carried out in the following manner:—I placed a freely movable weight upon the surface of the lid and found that while the case was vibrating the weight being unable to rest there, started to perform turning movements on the lid towards the center of vibration and finally coming to rest in a certain position on the lid. In this position, the vibration of the lid gradually subsided, resulting in a smooth operation of the motor. It was also established that a free weight which could control such vibration was less in weight than the

fixed weight employed in the preceding experiment.

This invention will be better understood from the following detailed description of the accompanying drawing in which:

Figure 1 shows the pot in a vertical section of the covering case attached to the frame of a spinning centrifugal motor.

Figure 2 shows a vertical section of the lid.

Figure 3 shows a front view of the pot and a vertical section of the case in which the lid itself is used as a movable weight.

Figure 4 shows a front view of the pot and a vertical section of the case in which the movable and revolving weight is placed on a special support attached to the case.

In Figure 1, 1 is a pot and 2 is a case covering the pot and similar to the pot in shape but a little larger in size allowing a narrow space around the pot. 3 is the motor frame and 4 is a lid covering the case having an opening 5 for the yarn. A ring-formed weight 6 is held on the flanges 7 and 8 is a narrow space between the weight and the flanges 7 which permits the ring to move and revolve freely within the flange. 9 is a guide member provided between the shaft and the base of the case and at the inside thereof.

In order to secure maximum efficiency it is advisable to insert some elastic material 10 under the ring 6 as illustrated in Figure 2, for the reason that when an elastic material is inserted between the ring 6 and the lid 4, the ring moves not only quietly but also smoothly, since it is not involved in vertical movements in conjunction with the lid, even if the lid is caused to move up and down.

In the arrangement shown in Figure 3, the weight of the lid itself is used to control the vibration. For this purpose the inner diameter

of the lid should be longer than the outer diameter of the brim so as to permit the lid to revolve on the brim of the case. The elastic material 10 is provided between the brim of the case and the lid. When the case is vibrated, the lid immediately starts to oscillate on the brim, but as soon as the center of gravity of the lid and the center of vibration coincide, the oscillations of the lid cease and the vibrations are put under complete control.

In the arrangement illustrated in Figure 4, the freely movable revolving ring 6 is placed on a support 11 carried by the base of the covering case. In this particular modification, the lid may be made light so as to facilitate its removal during operation. It is manifest that many variations of the above features may be resorted to, such as placing the guide at the upper part of the case between the case and the pot instead of at the base as illustrated in the drawing. It is also obvious that the guide may be connected with the pot or the shaft through the medium of a spherical contactor or some other contactor having a low frictional coefficient.

Having now particularly described the invention, I claim:—

In a spinning centrifugal motor device, in combination with a pot having a shaft adapted to be mounted on the motor frame, a case covering said pot and conforming substantially to the contour thereof, the walls of said case being spaced from said pot, whereby a chamber is formed intermediate said pot and said case, guiding means for said shaft carried by the inside wall of said case, a support carried by the outside wall of said case, and a movable and revolving ring freely mounted upon said support.

SHUZO ODAJIMA.
